UNITED STATES PATENT OFFICE.

JOSÉ MARIOJAS, OF EAGLE PASS, TEXAS.

ROTARY BIN.

Application filed January 7, 1924. Serial No. 684,884.

To all whom it may concern:

Be it known that I, JOSÉ MARIOJAS, citizen of the United States, residing at Eagle Pass, in the county of Maverick and State of Texas, have invented certain new and useful Improvements in Rotary Bins, of which the following is a specification.

The present invention relates to a rotary bin especially constructed for use under the counter of a grocery store or the like and has for its principal object to provide a device of this nature possessed of a simple and efficient construction, one which is reliable in use, inexpensive to manufacture, durable, convenient, and well adapted to the purpose for which it is designed.

With the above and numerous other objects in view as will appear as the description progresses, the invention resides in certain novel features of construction, and in the combination and arrangement of parts as will be hereinafter more fully described and claimed.

In the drawing:

Figure 1 is a detail perspective view of the device embodying my invention,

Figure 2 is a front elevation thereof showing the same in a closed position,

Figure 3 is a similar view showing the same in an open position,

Figure 4 is a vertical section on an enlarged scale taken substantially on the line 4-4 of Figure 3 looking in the direction of the arrow,

Figure 5 is a top plan view of the rotary member, and

Figure 6 is a top plan view of the bin.

Referring to the drawing in detail it will be seen that the device consists of a casing A and a rotary bin carrier B and the bin proper C.

The casing A is constructed with a circular bottom 1 having a semi-cylindrical wall 2 rising therefrom and supporting at its upper end a semi-circular top 3. The rotary member B consists of a door 5 the width of which is slightly smaller than the diameter of the bottom 1. This door 5 is provided with a pair of registering sleeves 6 in alignment with its vertical center, one sleeve 6 being disposed adjacent the bottom of the door and extending slightly there below. A shaft 7 is vertically disposed in the casing A rising from the center of the circular bottom 1 and passes through the sleeves 6. A washer 8 is disposed about

the shaft 7 so as to rest upon the bottom 1 and the lower end of the sleeve 6 at the bottom of the door 5 rests upon this washer 8 thereby allowing the door to be readily rotated or swung to an open position such as is shown in Figure 3 or to a closed position as is shown in Figure 2. These sleeves 6 are provided on the outer face of the door that is the face which is outermost when said door is in a closed position. A pair of handles 10 is disposed on the outer face of the door one adjacent each side thereof so that the same may be swung to an open position in either direction. As is shown particularly well in Figure 4 the inner face of the door 5 has mounted thereon a pair of side strips 11 the lower portions of which are broader than the upper portions. A block 12 is disposed on this inner face of the door adjacent the bottom thereof between the side strips 11 and a semi-circular platform 13 is fixed thereto. A triangular shaped brace 14 is attached to the block intermediate its ends so as to brace this platform 13. A bracing strip 15 is disposed on the inner face of the door 5 at its upper edge.

The bin C is constructed with a semi-circular bottom 20, a straight wall 21 and a curved wall 22. This wall 22 is curved concentric with the curved edge of the platform 13 and with the semi-cylindrical wall 2 of the casing. The bin C rests upon the platform 13 and it is to be noted that the outer faces of the side strips 11 are also curved concentric with the wall 22.

In using the device I find it convenient to have the same located under the counter of a store for instance and when it is desired to take something from the bin C the door 5 may be very easily swung to an open position. It is evident, of course, that the device may be used in numerous other ways without departing from the spirit of this invention. I also desire to point out that numerous changes in the details of construction, and in the combination and arrangement of parts may be resorted to without departing from the spirit and scope of the invention as hereinafter claimed or sacrificing any of its advantages.

Having thus described my invention what I claim as new is:

In a device of the class described, a casing including a circular bottom and a semi-circular top with a semi-cylindrical wall

therebetween, a shaft extending between the top and bottom, a door having a pair of sleeves on one side thereof for receiving the shaft, one of said sleeves extending below the bottom edge of the door, a washer on the shaft resting on the bottom of the casing so as to be engaged by the bottom sleeve on the door, and a platform on the other side of said door for supporting a bin.

In testimony whereof I affix my signature.

10
JOSÉ MARIOJAS.
